UNITED STATES PATENT OFFICE.

WALTER M. INGRAM, OF SUDBROOK PARK, MARYLAND, ASSIGNOR, BY DIRECT AND MESNE ASSIGNMENTS, TO THE SANITARY TEA BAGGING COMPANY, OF BALTIMORE, MARYLAND, A CORPORATION OF MARYLAND.

OVERSEAMING MACHINE.

Application filed June 19, 1925. Serial No. 38,236.

This invention relates to over-seaming machines and has for an object to provide an over-seaming machine especially adapted for operating upon coarse fabric with cut edges from which extend short raveling threads and to provide means for laying down these extended threads to produce a smooth over-seam.

A further object of the invention is to provide in an over-seaming sewing machine means whereby the stitch is formed by the needle and looper over an inclined spoon and caused to slide forward over the extremity of said spoon by the tension of the thread to lay down the raveling threads in smooth serial relation.

A further object of the invention is to provide additional frictional tension in the thread take-up for the purpose of causing the stitch formed over the spoon to slide forward as noted.

A further object of the invention is to provide an improved type of over-turning spoon and means for holding the edge of the fabric within such spoon to form an over-turned edge upon which the forwardly sliding stitch operates.

With these and other objects in view, the invention comprises certain novel parts, elements, units, combinations, constructions, interactions, mechanical movements and functions, together with mechanical functional equivalents thereof as will be hereinafter more fully described and claimed.

In the drawings:

Figure 1 is a perspective view of an over-seaming sewing machine of a known type with the improvement applied thereto.

Figure 2 is an enlarged perspective view of the needle, looper, take-up and over-seaming spoon.

Figure 3 is a top plan view of the over-seaming spoon showing its relation to the needle, the looper and the stitch.

Figure 4 is a top plan view of the spoon structure removed.

Figure 5 is a sectional view through the spoon as indicated by line 5-5 of Figure 4.

Like characters of reference indicate corresponding parts throughout the several views.

The present invention is applied to an over-seaming sewing machine of a well known type employing a curved needle A,

a looper B, feed C, presser foot D, needle-actuating mechanism E, and other well known parts of machines of the type.

Properly positioned adjacent the feed C is the over-turning spoon 10 which forms a material part of the present invention carried by a preferably integral plate 11 which is attached to the body of the machine in any convenient manner as by a screw at 12.

The relation of this spoon 10 to the feed C is such that as the fabric, a fragment of which is represented at 13, is fed through the machine, the edge is brought into engagement with the spoon and by the curvature of the spoon represented in section at 14 at Figure 5 is turned over above the top of the fabric.

As explained in the object of invention, the machine is intended to operate particularly with a fabric of coarse texture having a raw cut edge from which would naturally extend short threads or ravelings, as indicated at 14, and these threads or ravelings, while turned over with the edge, stand up in a more or less untidy manner.

The relation of the spoon 10 to the needle A and the looper B, is such that the extreme end 15 of said spoon lies between the path of the needle and looper when coacting so that the stitch formed by the needle and looper is drawn over and rests upon the top of the spoon 10 adjacent to the nose 15 as illustrated more particularly at Figure 3.

The nose 15 of the spoon 10 is curved and inclined, as shown more particularly at Figure 2, so that the tension of the thread forming the stitch and extending between the needle and the looper as illustrated at Figure 3 will cause the stitch to slide forwardly over the nose 15 of the spoon and carry therewith the upstanding extended ends 14 of the cut fabric 13 laying these fabrics down neatly into the seam formed by the successive stitches.

To insure the proper sliding action of the stitch over the nose of the spoon, more than ordinary tension is required upon the needle thread 16. To this end the take-up 17, which in its mechanical movement and general form is the accepted type of take-up, is provided with additional tension means comprising the holes 18 and 19 which are in

addition and supplemental to the regular thread opening 20 of the recognized type of take-up. The needle thread is threaded through this take-up as indicated at Figure 5 2 and also at Figure 1, or in such other manner as may be found necessary or desirable for supplementing and augmenting the tension upon the needle thread 16.

The take-up 17, as is well known in this 10 type of machine, moves toward and away from the looper B following an arcuate path the resultant of centers of oscillation at F and G. This arcuate movement of the take-up 17 is somewhat analogous to the movement 15 of the needle A but departs from synchronous movement sufficiently to exert tension upon the thread in proper timed relation to the co-action of the looper. So that this take-up may exert the necessary tension 20 upon the needle thread 16, a guide 17' is attached to the head of the machine through which the thread extends. From the tension H the needle thread, indicated at 16', passes about a pin 17'' returning as 16'' to 25 the take-up. This arrangement of the pin and guide in combination with the take-up embodying the additional tension openings 18 and 19 provides means for exerting sufficient tension upon the needle to cause the 30 stitch to slip over the nose 15 of the spoon as noted.

To properly hold the edge of the fabric within the spoon while the stitch is being 35 formed and the raveling threads being laid down by the sliding stitch, a finger 21 is positioned within the curvature of the spoon, the end of which extends adjacent to the nose 15 of the spoon, stopping sufficiently 40 short thereof to enable it to be lifted to the position 21' as shown in dotted lines at Figure 3 when a new fabric is to be inserted into sewing position. To lift this finger from the operative to its raised position, it is mounted upon an arm 22 pivoted at 23. 45 While it is the intent that this arm 22 shall be lifted by the same means which lifts the pressure foot to provide for the insertion of new fabric and means 24 provided for attachment of such lifting means, such lifting means is not included in the present disclosure and any means for lifting the finger 50 21 at any proper time is included in the present invention.

Also mounted upon the body of the 55 machine is a shear 25 properly positioned to at times cut the thread, but the means for actuating this shear in proper timed relation to the other parts of the mechanism are not here shown and the shear is, therefore, not 60 claimed as part of this invention.

The present invention is intended to operate in conjunction with a machine for bagging measured quantities of commodity and simultaneously producing a bag for such 65 commodity, which bag is made of coarsely

woven fabric material cut in circular disks. The particular type of bagging machine referred to provides means for rotating the disks in proper operating relation to the sewing machine, but it is to be understood that, while this particular over-seaming machine is especially adapted for co-acting with such bagging machine, it is not limited in its scope thereto and includes over-seaming any raw edge fabric wherein extended threads require laying down to produce a neat appearing over-seam.

In operation, therefore the fabric whether of the circular disk type or other type is introduced into the machine by the raising of the finger 21 and presser foot D and, when so introduced, the presser foot and finger are returned to operative position and the machine operates upon the fabric by advancing it through the medium of the feed in the usual manner. As the fabric is advanced, the cut edge is propelled within the curvature of the spoon 10 to turn up the raw cut edge over the finger 21 and in this condition is fed to the position within the spoon between the needle A and the looper B. The stitch is formed between the needle and the looper in the usual manner and the showing of threads between the needle and the looper as at Figure 3 is only meant to illustrate the position of the stitch and not the exact formation of the stitch which is immaterial to the present invention, the form of the stitch produced by this mechanism being already well known in the art. The spoon underlying the extended looper tends to form the stitch between the looper and the needle over and upon the top of the spoon and by reason of the tension upon the needle thread produced by the improved type of take-up 17 causes the stitch to slide down the inclined top surface of the spoon in advance of the forward feed of the work, thus advancing and carrying with it in its sliding action the upwardly extended cut ends of the raveling threads. This causes the raveling threads to be laid down in series under each stitch so that the successive stitches produce in relation to this raw cut edge a neat appearing and firmly connected over-seam.

What I claim to be new is:

1. In an over-seaming machine, the combination with a needle and looper of a spoon introduced between the the needle and looper in such position that the stitch formed by the needle and looper is formed upon the top of the spoon, said spoon being provided with an inclined extremity over which said stitch so formed slides in the direction of the feed of the work and means to hold the work within the curvature of the spoon.

2. In an over-seaming machine, the combination with a needle and looper of a spoon underlying the advanced position of the

looper and between the needle and the withdrawn position of the looper, said spoon extending a limited distance in advance of the position of the stitch formed upon the top of said spoon by the movement of the looper away from the needle and a work holding member removably positioned within the curvature of the spoon.

3. In an over-seaming machine, the combination with a needle and looper, of a spoon underlying the advanced position of the looper, said spoon being curved to form a channel upon the side adjacent the needle and extended in advance of the position of the looper, and a finger positioned within the curvature of the spoon adapted to hold the advancing work within the curvature.

4. In an over-seaming machine, the combination with a needle and stitch looper, of a spoon underlying the advanced position of the looper and between the needle and the

retracted position of the looper, said spoon being curved to present its channeled side toward the needle and its advanced end in advance of the path of movement of the looper, and a removable finger positioned within the curavature of the spoon adapted to hold the edge of the work within said curvature.

5. In an over-seaming machine, the combination with a needle and a looper, of a spoon underlying the advanced position of the looper and in position to support the stitch upon its upper surface, and a thread take-up provided with a plurality of thread openings forming a tension for the needle thread, adapted to taunt the stitch to cause it to slide forwardly over the extremity of the spoon.

In testimony whereof I affix my signature.

WALTER M. INGRAM.
